(Cl. D26—1)

To all whom it may concern:

Be it known that we, James D. Burke and Fuller A. Crooks, citizens of the United States of America, residing at Los Angeles, in the county of Los Angeles, State of California, have invented a new, original and ornamental Design for an Armature for Electromagnet, of which the following is a specification, reference being had to the accompanying drawing, forming a part thereof.

Fig. 1 is a perspective view showing the front and one side of an armature for electromagnet, showing our new design.

Fig. 2 is a perspective view showing the rear and other side of said armature,

Fig. 3 is a front elevational view of said armature,

Fig. 4 is a side elevational view of the same,

Fig. 5 is a rear elevational view of the same, and

Fig. 6 is a bottom plan view of the same.

We claim:

The ornamental design for an armature for electromagnet, as shown.
